DESIGN FOR AN ENSEMBLE DRESS

Irwin Kranz, New York, N. Y.

Application July 31, 1936, Serial No. 64,153

Term of patent 3½ years

To all whom it may concern:

Be it known that I, Irwin Kranz, a citizen of the United States of America, residing in the city of New York, county of New York, and State of New York, have invented a new, original, and ornamental Design for an Ensemble Dress of which the following is a specification, reference being had to the accompanying drawing, forming part thereof.

Fig. 1 is a front view of an ensemble dress showing my new design.

Fig. 2 is a rear view of the ensemble dress shown in Fig. 1.

Fig. 3 is a front view of the ensemble dress without the coat.

Fig. 4 is a rear view of Fig. 3.

My design is characterized by the combination of an ensemble dress, having a short coat with ribboned loops on the shoulders and a dress having the ribboned loops on the neck portion as shown. The bottom portion of the coat tucks into the belt of the dress as shown.

I claim:

The ornamental design for an ensemble dress, substantially as shown and described.

IRWIN KRANZ.
